Primary Examiner — Susan Bennett Hattan*Assistant Examiner* — Marie Fast Horse(74) *Attorney, Agent, or Firm* — Harness, Dickey & Pierce, P.L.C.(57) **CLAIM**

The ornamental design for the data processing and transmission device, as shown and described above.

DESCRIPTION

FIG. 1 is a top front perspective view of a data processing and transmission device showing our new design;

FIG. 2 is a bottom front perspective view thereof;

FIG. 3 is a bottom rear perspective view thereof;

FIG. 4 is a front elevational view thereof;

FIG. 5 is a rear elevational view thereof;

FIG. 6 is a top view thereof;

FIG. 7 is a bottom view thereof;

FIG. 8 is a left side view thereof; and,

FIG. 9 is a right side view thereof.
